UNITED STATES PATENT OFFICE.

BENJAMIN F. OREWILER, OF CHICAGO, ILLINOIS.

ATTACHMENT FOR GARMENT-SUPPORTERS.

1,183,903.

Specification of Letters Patent. Patented May 23, 1916.

Application filed April 9, 1915. Serial No. 20,194.

To all whom it may concern:

Be it known that I, BENJAMIN F. OREWILER, a citizen of the United States, residing at Chicago, in the county of Cook and State of Illinois, have invented certain new and useful Improvements in Attachments for Garment-Supporters, of which the following is a specification.

The present invention relates to an attachment in the form of a connecting piece adapted and intended to be used in conjunction with garment supporters, as for instance the ordinary garter.

The object of the invention is to configure a single piece of metal in a manner whereby it will serve to; first, provide a connecting piece between the suspending strap and the garment clasp; second, to act as a retainer for the upper end of the non-extensible fabric or tape of the garment clasp; third, to retain the free ends of the loop of the garment clasp; and fourth, to reinforce and strengthen such looped portion against an undue separating or springing action.

A further object of the invention is to make the attachment of a simple design whereby it is easily and cheaply manufactured, and can be readily and quickly applied to the parts of the garter with which it is associated.

The invention further consists in the features of construction and combinations of parts hereinafter described and claimed.

In the drawings: Figure 1 is a front view of a garter with the device or attachment of the present invention in operative position; Fig. 2 is an edge view showing the attachment of the present invention together with the lower part of the suspending strap in section and the garter clasp in elevation; Fig. 3 is a detail showing a section through the attachment of the present invention and showing the upper part of the loop member and tape of the garment clasp held in position; Fig. 4 is a front view of the attachment of the present invention; and Fig. 5 is a section on line 5-5 of Fig. 4 looking in the direction of the arrow and showing the tape of the garment clasp in clamped or secured position.

In connection with the use of garment supporters a link or connecting member is employed for joining the garment clasp to the elastic suspending strap, and in order to cover the metal upon the back of the clasp a strip of fabric, usually non-elastic tape, is employed, and, of course, means must be provided for securing and holding this tape in place. The clasp employs a looped member, which is contracted at its lower end and enlarged medially thereof. The lower contracted end embraces the stud and serves to hold the fabric in wrapped condition about the stud. Means must be provided for reinforcing or strengthening this looped member so that it will not possess too great an amount of spring property, otherwise it would spring apart to such an extent in use, as to eliminate its value as a means for holding the fabric in wrapped condition about the stud, and so far as I am aware, there has never been produced an attachment formed of a single piece of metal which will serve as a means of connecting the garment clasp and suspending strap, hold one end of the garment clasp tape, and strengthen and reinforce the loop member of the garment clasp.

It is the primary aim and object of the present invention to carry out these functions by means of a single member configured to bring about such results.

Referring to the drawings, and particularly to Fig. 1, a suspending strap 6 is shown of the ordinary nature, to which is attached a buckle 7 for adjusting the length thereof. The buckle, however, forms no part of the present invention, and, of course, can be of any suitable style. The clamping portion of the garment supporter consists of a stud base 8 from which rises a stud 9, both the base and stud being of any suitable construction. A tape or fabric 10 is attached to said stud base in any suitable manner, and this tape, as will be seen from the drawings, extends along the back of the clamping portion or clasp, and serves to prevent any metal of the clasp from coming in contact with the wearer. The other part of the clamping portion consists of a looped mem-

ber 11 terminating at its lower end in a neck 12 and formed with a medial enlargement 13. This member is of the old and well known construction with the exception that 5 certain parts are of novel configuration as will be hereinafter pointed out.

The device of the present invention consists of a member formed of a single piece of metal and designated generally by the 10 numeral 14. This member is provided at its upper end with a slot 15 and the upper part of the member consists of a bar 16, which, when the member is attached to the suspending strap 6, lies within the loop portion of said strap, as will be seen from Fig. 2, so that by provision of this slot and bar the member 14 serves as a means for joining or connecting the suspending strap and the garment clasp. The lower end of the member 20 is in the form of a depending neck 17, of a reduced width from the width of the remainder of the body, and this neck is bent back upon itself to form a U-shaped piece 18. The portion 19 of the U-shaped 25 piece which lies to the rear, terminates in a toothed edge angularly extending flange 20, the toothed edge of which alines with a slot 21 in the body of the member. The slot 21 lies below the slot 15 and for convenience 30 may be termed the lower slot.

The tape 10 is folded over the toothed edge of the flange 20, as will be seen from Figs. 2 and 3, and then by a swedging action the flange is forced forward crowding the 35 tape into the slot 21, as will be apparent from Fig. 5, thus securing this end of the tape in position. The teeth of the flange 20 are not intended to be sharp, since it is not desired to have a penetration or puncturing 40 of the tape, but rather a forcing or crowding of the tape through the slot. The bottom wall of the U-shaped member 18 is cut away, as at 22. The free ends of the loop member 11 are inserted into the U-shaped 45 member 18, and the extremities 23 of the ends of the member 11 are bent slightly downward so that they project through the opening 22, as will be seen from Fig. 1, and when the ends are thus configured the loop 50 member is held by the U-shaped portion against undue outward springing movement, and thus the loop member 11 is reinforced or strengthened against an undue springing action when in use, and this bending of the 55 ends of the loop members so that they project through a slot is deemed to be a novel configuration of the end portions of the loop member.

From the foregoing it will be seen that the 60 member 14 serves as a means for joining the elastic suspending strap to the garment clasp; serves as a means for retaining one end of the garment clasp tape in position; serves to retain the free ends of the wire

loop of the garment clasp in position; and 65 serves to reinforce and strengthen said wire loop against an undue outward springing action. It will also be apparent that the device is very cheap and simple of construction, and that the application of it to the 70 other parts of a garter or garment supporter is very simple.

I claim:

1. In combination with a suspending strap and garment clasp, a member formed of a single piece of metal having a slot therein and bent to provide a U-shaped portion adjacent its lower edge within which the ends of the garment clasp loop may lie, means for holding within the U-shaped portion the 75 ends of the garment clasp loop against an outward spreading movement, a flanged upper end on the U-shaped portion alining with the slot and acting when pressed toward the slot to force one end of the garment clasp tape therein to retain that end of the tape in position, and means above said slot for retaining the suspending strap, substantially as described.

2. A device of the character specified, 90 consisting of a body formed of a single piece of metal, and comprising a relatively wide upper portion and a relatively reduced lower portion, means on the upper portion for receiving and retaining a suspending strap, 95 and said upper portion being formed with a slot at the lower part thereof, said lower portion of the body being bent back upon itself to form a U-shaped section, a flange on the upper end of said U-shaped section 100 alined with said slot in said upper portion, and the bottom wall of the U-shaped section having a central notch therein, substantially as described.

3. A device of the character specified 105 consisting of a body formed of a single piece of metal and having a slot adjacent its upper edge, the lower portion of said body being bent back upon itself to form a U-shaped section, said body being provided with a second slot below the first mentioned slot, a flanged upper end on the U-shaped section, 110 and said flanged end and second slot alining with one another, substantially as described.

4. A device of the character specified 115 consisting of a body formed of a single piece of metal and having a slot adjacent its upper edge, the lower portion of said body being bent back upon itself to form a U-shaped section, said body being provided with a second slot below the first mentioned slot, a flanged upper end on the U-shaped section, 120 said flanged end and second slot alining with one another, and the bottom wall of the U-shaped section having a notch cut therein, 125 substantially as described.

5. A device of the character specified consisting of a body formed of a single piece of

metal and provided with a lower slot and an upper slot, the lower portion of said body being bent back upon itself to form a U-shaped section, a notch in the bottom wall 5 of the U-shaped section, a flanged upper end on the U-shaped section provided with a serrated edge, and said flanged end alining

with said lower slot, substantially as described.

B. F. OREWILER.
